REINFORCING BAR SUPPORT FOR ROAD PAVING AND THE LIKE AND PROCESS OF
ROAD PAVING

Application filed April 4, 1929. Serial No. 352,438.

This invention relates to removable concrete reenforcing bar supports for use in concrete road paving, and other concrete work, and also relates to a process of road paving 5 wherein removable concrete reenforcing bar supports are used.

At the present time, most if not all of the States, have certain specifications for their standard type of concrete pavement. Most 10 of these specifications call for the use of certain types of reenforcing bars which must be embedded in the concrete of the pavement in spaced relation from the subgrade for the pavement. Bar support pins are now utilized 15 to hold the reenforcing bars in proper spaced relation from the subgrade, so that the concrete forming the major portion of the pavement may be properly poured about the reenforcing bars. The support pins now com- 20 monly used are irremovably attached to the reenforcing bars and they are left embedded in the pavement after the concrete has been poured. These pins add considerably to the 25 cost of the pavement, and often cause delay in constructing the pavement, inasmuch as a large quantity of the pins must be at all times 30 on hand for use and they must be distributed along the line of wav of the pavement for use. Although certain types of removable 35 reenforcing bar support pins have been hereto devised, for use in road paving, such pins can generally only be used where certain parts of the reenforcing structure can also be removed.

It is the object of the present invention, therefore, to provide novel and improved supports for the reenforcing bars used in concrete paving and the like, which are adapted 40 to hold the reenforcing bars in spaced relation above the subgrade for a pavement or other surface to permit concrete to be poured about the reenforcing bars, whereupon the supports may be removed for further use.

It is another object of the present invention 45 to provide a novel and improved process for concrete road paving, whereby removable reenforcing bar supports may be utilized.

To these ends, the invention consists in the 50 novel parts and novel combinations of parts and novel processes and novel steps in the

processes, hereinafter defined in the claims, and described in the following specification, made in connection with the accompanying drawings, wherein like reference characters refer to the same or similar parts throughout 55 the various views and, in which,

Fig. 1 is a vertical transverse section through a freshly poured concrete pavement, wherein the reenforcing bar supports of the present invention are utilized; 60

Fig. 2 is a plan view of a portion of the said pavement;

Fig. 3 is a vertical section shown in an enlarged scale and taken on the line 3—3 of Fig. 2; 65

Fig. 4 is a vertical section in an enlarged scale taken on the line 4—4 of Fig. 2;

Fig. 5 is a plan view illustrating the central bar support as shown in Fig. 3, the concrete being removed and the bar support be- 70 ing shown in full lines in one position and in dotted lines in a position that it will assume when being removed;

Fig. 6 is a vertical section in an enlarged scale taken on the line 6—6 of Fig. 2, and 75 illustrating one type of side bar support that may be used, the support being shown in full lines in one position and being indicated in dotted lines in a position that it will assume during the removal thereof; 80

Fig. 7 is a view in side elevation of the side bar support illustrated in Fig. 6 in applied position, the concrete not being shown;

Fig. 8 is a vertical section similar to Fig. 6 of a slightly different type of side bar sup- 85 port, and

Fig. 9 is a plan view of the side bar sup- 90 port illustrated in Fig. 8, and showing the same in applied position in full lines, and in the position that it will assume while being removed in dotted lines.

Referring to the drawings, a standard concrete road section made according to the State of Iowa specifications is illustrated, and although the bar supports of the present invention and the processes of the invention employed, may be utilized in building roads of practically any desired type, the standard Iowa section serves as a good example to show the manner in which the present in- 95 100

vention is employed. The subgrade of the roadway is designated by the numeral 10, and it is over this subgrade that the concrete roadway is poured. Side forms 11 are laid at the two side edges of the subgrade, to extend longitudinally thereof, and the side forms illustrated are of channel-shape in cross section, the lower horizontal flange of each form resting on the subgrade 10 and being considerably wider than the upper flange of the form. A so-called center parting strip 12 is employed which is vertically mounted at the transverse center of the subgrade 10 to extend longitudinally thereof. The center parting strip is secured to the subgrade as by means of light pins 13, which run downwardly into the subgrade 10, and project through a V-shaped portion, or otherwise polygonal-shaped portion of the central parting strip. It is the usual practice to support the central portions of transversely extending dowel bars, such as the dowel bars 14, in the center parting strip 12 at spaced intervals longitudinally thereof. Holes are cut in the V-shaped portion 12a of the parting strips and dowel bars 14 are run through these holes, so that the dowel bars will project upwardly in spaced relation from the subgrade 10. To support the ends of the dowel bars 14, and in accordance with the present invention, I have provided my central removable bar supports 15. The supports 15 may be formed from strap iron, or similar material as illustrated, and the lower end of each support is reduced to form ground engaging shoulders 15a and a reduced portion 15b pointed at its lower end and adapted to be driven into the ground. A notch 15c is cut in one side of the support 15, and this notch is open at its upper and outer sides. A finger 15d projects laterally outwardly and is curved slightly upwardly adjacent the notch, to form with the notched portion of the support a shallow ledge upon which an end of one of the dowel bars 14 may be supported to hold the same in properly spaced relation from the subgrade 10. The support 15 will, of course, be driven into the ground of the subgrade 10 until the shoulders 15a limit the downward movement of the support by engagement with the ground, and the support 15 from the shoulders 15a to the upper end thereof will be of greater height than the desired thickness of the concrete pavement when finished, so that the upper end of the support may be grasped above the poured concrete of the pavement for removal of the support. As illustrated in enlarged scale Fig. 3, two of the central supports 15 will be provided for supporting each dowel bar 14 for a given section of pavement, and the dowel bars will thus be evenly supported in horizontal arrangement on the ledges formed by the notches 15c and the fingers 15d. It is usual to secure central longitudinal reenforcing

bars 16 to the dowel bars 14 as by wires 17, one or more of the bars 16 being situated at either side of the center parting strip 12. Accordingly, the supports 15 will act to not only support the dowel bars 14, but also to support the central longitudinal reenforcing bars 16 secured to the dowel bars.

One or more longitudinal reenforcing bars 17 are usually used to reinforce the concrete pavement adjacent the side mold forms 11. In the drawings, two of these bars 17 are shown. Two slightly different types of side supports are illustrated in the drawings for supporting the side bars 17. Referring to Figs. 1, 2, 6 and 7, side supports 18 are illustrated. Each support 18 consists of a member formed preferably from strap iron and having a comparatively long vertical portion 18a with its lower end and adapted to bear against the ground of the subgrade 10 in inwardly spaced arrangement from the side forms 11, a horizontal portion 18b joining the upper end of the vertical portion 18a and of such length as to extend over to the side form 11, a short vertical portion 18c joining the outer end of the horizontal portion 18b and running upwardly therefrom to bear against the inner edge of the vertical flange of the side form 11, a horizontal portion 18d joining the upper end of the vertical portion 18c and running outwardly therefrom over the top horizontal flange of the side form 11, and a short diagonal portion 18e joining the outer end of the horizontal portion 18d and adapted to be used as a handle. Secured to one side of the vertical portion 18a are one or more curved fingers 18f which run downwardly adjacent the vertical portion 18a for a short distance and project outwardly and curve slightly upwardly therefrom. The said fingers 18f have the combined function of notches 15c and the fingers 15d of the supports 15 and like the notches 15c and fingers 15b, the fingers 18f form ledges open at their upper and outer sides within which the side bars 17 may be carried. In the drawings, the support 18 is illustrated as having two of the fingers 18f secured thereto, to support two bars 17 and these fingers are spaced upwardly from the lower end of the vertical portion 18a and are spaced from each other. It will be understood that any desired number of the fingers may be provided.

In Figs. 8 and 9, a slightly different type of side support 19 is illustrated for use in supporting the side bars 17. The side support 19 is constructed very much like the central support 15, with the exception that the side support 19 carries adjacent its upper end an arm 19e which projects laterally from the support and is adapted to bear against the side mold form 11, or some other relatively fixed member. The support 19 has ground contacting shoulders 19a spaced up-

wardly a short distance from the lower end thereof and similar to the shoulders 15a, and also has a pointed reduced portion 19b adapted to be driven into the ground and corresponding to the pointed reduced portion 15b of the support 15. One or more notches 19c are formed in the support 19 at one side thereof and these notches, like the notches 15c, have co-operating outwardly 5 and slightly upwardly projecting fingers 19d corresponding to the fingers 15b and forming ledges open above and outwardly from the support 19 to receive the side bars 17. It should be here noted that both the supports 15 and the supports 19 are bulged outwardly at the side opposite the notches 15c and 19c respectively, in order that the said supports will not be weakened by the formation of the said notches.

10 In utilizing the supports of the present invention in road paving, dowel bars 14 and the central reenforcing bars 16 for a section to be paved, will be supported by the supports 15 in the desired position above the subgrade 10, and the side bars 17 will be supported in the desired position above the subgrade 10 by means of either the supports 18 or 19. Plastic concrete 20 may be dumped on to the subgrade 10 in piles between the 15 outer ends of the dowel bars 14 and the side reenforcing bars 17. The concrete will run against the supports 18 or 19 in a general outwardly direction and it is for this reason that the portions 18c, 18d and 18e of the support 18 are provided, and it is also for this reason that the arm 19e of the support 19 is provided. As the outer end portion 18b and the portions 18c and 18d of the support 18 will bear against the side mold form 11, the 20 upper portion of the support will have a bearing against the side mold form 11 to resist the outward movement of the concrete as it is poured and thus prevent the support 18 from being carried away by the concrete. Similarly as the arm 19e of the support 19 bears against the side mold form 11, the side mold form 11 will brace the support 19 to resist the outward movement of the concrete 25 20, and will thus prevent the support 19 from being carried away by the moving concrete. The plastic concrete 20 will be poured on to the subgrade 10 until the desired thickness of the concrete for the roadway is obtained. As this concrete usually 30 consists of large quantities of broken stone, the concrete will work beneath the dowel bars 14, central reenforcing bars 16 and outer reenforcing bars 17. When the desired thickness of concrete has been poured 35 and before the top surface of the concrete has been finished off by a finishing machine, the supports 15 and 18 or 19 will be removed. To remove the supports 15, the upper ends of the supports need merely be grasped and 40 the supports turned as from the full line position illustrated in Fig. 5, to the dotted line position illustrated in Fig. 5, whereupon the supports may be raised upwardly and outwardly from the subgrade 10 and the concrete 20. As the supports 15 are initially 45 turned, the fingers 15d will cam the dowel bars slightly upwardly in the concrete to allow the fingers 15d to pass to one side of the dowel bars, thus disengaging supports 15 completely from the dowel bars. If the side 50 supports 18 are used, they can be readily disengaged from the side bars 17 by merely grasping handles 18e and turning the bars upwardly from the position illustrated in full lines Fig. 6, to the position illustrated 55 in dotted lines Fig. 6, whereupon the supports can be raised out of the concrete 20. As the supports 18 are initially tipped upwardly, the fingers 18f will be withdrawn from beneath the bars 17 to completely disengage the supports 18 from the bars. If desired, the supports 18 can be raised slightly and turned about a vertical axis to disengage the same from the bars 17, whereupon the fingers 18f will cam the bars 17 60 upwardly slightly until the fingers are disposed at one side of the bars. If the supports 19 are used, they will be disengaged from the bars 17 in a manner similar to the manner of disengagement of the supports 15 65 from the dowel bars 14. The upper ends of the supports 19 will be grasped and the supports will be swung from the full line position shown in Fig. 9, to the dotted line position shown in Fig. 9, whereupon the 70 supports may be withdrawn from the subgrade 10 and the concrete 20. The fingers 19d during the initial turning movement of the supports 19, will cam the bars 17 upwardly slightly to permit the fingers to pass 75 to one side of the bars. After the supports have been completely removed, the concrete 20 will hold various bars 14, 16 and 17 in position above the subgrade 10, so that the said bars will be firmly embedded in the 80 concrete, to brace and strengthen the same. The broken rock used in the concrete will prevent the bars from sinking until the concrete is set.

75 In working on a paving job, only a few 85 of the supports 15 and 18 or 19 are required for constructing an indefinite length of the pavement. As the supports 15 and 18 or 19 are removed from the reenforcing bars and concrete, they will be thrown ahead of 90 the section under construction to a point where the next section of paving is to be constructed where they will be readily accessible for further use. The expense of supplying a large number of bar support 95 pins for each section of pavement is, therefore, eliminated by use of the present supports and it will be unnecessary to have on hand a large quantity of bar supports.

100 The supports and processes of paving 105

above described, have been used in actual practice with success. The supports are simple in construction, are easy to handle and can be used without requiring any more labor than has heretofore been required in using other types of bar supports.

It will, of course, be understood that various changes may be made in the form, details, arrangement and proportions of the bar supports and that changes may be made in the processes of paving, as above described, without departing from the scope of the present invention.

What is claimed is:

1. A removable bar support for use in road paving and the like, having a lower portion adapted to bear against and be supported from the ground, a finger projecting outwardly from one side of the support for a short distance and curving slightly upwardly at its outer end, said finger being disposed in upwardly spaced relation from the ground bearing portion of the support, said finger being adapted to receive and hold a concrete reenforcing bar until plastic concrete has been poured thereabouts, said support being movable from a reenforcing bar by a turning movement of the support without substantially lowering the same, the curved portion of said finger acting as a cam on the reenforcing bar to raise the same slightly and thereby permit the finger to be carried to one side of the bar.
2. A removable bar support for use in concrete road paving and the like, comprising a substantially vertical member having its lower end adapted to rest on the ground, a finger projecting laterally therefrom for a short distance and curving upwardly slightly at its outer end to receive and hold a concrete reenforcing bar, an arm projecting laterally from one side of said member, said arm being bent to fit over and embrace a side mold form at opposite sides thereof.
3. A removable bar support for use in concrete road paving, comprising a vertical member having its lower end adapted to rest on the ground, a finger projecting laterally from one side of said member and curving upwardly slightly at its outer end to receive and hold a concrete reenforcing bar, an arm extending from one side of said member and having a portion projecting laterally therefrom for some distance, said arm having a vertical portion joining said laterally projecting portion and adapted to abut the inner side of a side mold form, said arm having a horizontal portion joining said vertical portion and adapted to extend over the top of the mold form and said arm having a downwardly and outwardly inclined portion joining said horizontal portion and adapted to bear against the outer side of the mold form.

In testimony whereof I affix my signature.

ERNEST WILBERT HALLETT.
